UNITED STATES PATENT OFFICE.

EDWARD T. HURLEY, OF CINCINNATI, OHIO.

CLAMP FOR ARTISTS' CANVASES.

Application filed March 17, 1920. Serial No. 366,488.

To all whom it may concern:

Be it known that I, EDWARD T. HURLEY, a citizen of the United States of America, and a resident of Cincinnati, in the county of 5 Hamilton and State of Ohio, have invented a new and useful Improvement in Clamps for Artists' Canvases, of which the following is a specification.

An object of my invention is to provide 10 clamps for holding artist's canvases that will preclude possible contact between the painted surfaces when the clamps are applied. This and other objects are attained by the means described herein and disclosed in the 15 accompanying drawings, in which;

Fig. 1 is a plan view of a clamp embodying my invention in an extended position.

Fig. 2 is a sectional view on an enlarged scale of two canvases in condition for transportation and being secured by a clamp.

Fig. 3 is an end view on an enlarged scale of an attached clamp.

Fig. 4 is a perspective view on reduced scale of canvases secured by several clamps.

25 My invention consists of two clamps pivotally attached at one end, and having thumb screws adapted to secure the frames holding canvases.

Clamps A and B are hingedly attached by 30 pivot C. The thumb screws *a* and *b* are employed to secure the frames D in the clamps. When the canvas holding frames are to be placed in the clamps, the clamps are extended to assume a position as shown in Fig. 1, 35 thereby avoiding possible contact between the wet surfaces. After one or two clamps have been attached to the same sections of the canvas holding frames the canvases and clamps are moved upon the pivots C until 40 the canvases assume a parallel position as shown in Figs. 2, 3, and 4. Additional clamps are then attached to the opposite edges of the canvas holding frames as shown in Fig. 4. A strap or carrier can be attached to the clamps through the openings 45

*a*¹ and *b*¹, for convenience in carrying the canvas.

These clamps may be utilized to engage and secure two sections of stage scenery.

What I claim is.

1. A holder for artists' canvases comprising two clamps, a pivot connecting said clamps and means for spacing and holding in parallelism a pair of canvases.

2. A holder for artists' canvases comprising two U shaped members, a pivot connecting said members, means on each member for positioning a canvas thereon, the members being adapted to be moved to an extended position to permit positioning of the 55 canvases thereon and to be moved to contracted positions whereby the faces of the canvases are untouched and retained in spaced relation to one another.

3. A holder for artists' canvases comprising two clamps, each having means to position a canvas thereon, and means hingedly connecting the clamps, whereby the canvases may assume a relatively extended position and a relatively contracted position having 60 70 their opposed faces spaced from one another and extending in substantial parallelism.

4. A holder for artists' canvases comprising two clamps each being of a structure such that each clamp may be mounted on the 75 inner and outer edges of the frame of an artist's canvas and leave the canvas face free from engagement with any part of said clamps, and a hinged connection between the clamps whereby the clamps may be caused to 80 assume an extended position for mounting each clamp on separate canvases and to assume a contracted position for holding the canvases in a relation such that the faces of the canvases are disposed in spaced parallelism.

In witness whereof, I have hereunto subscribed my name this 13th day of March, 1920.

EDWARD T. HURLEY.
